(57) **CLAIM**

The ornamental design for a tile alignment and leveling device, as shown and described.

DESCRIPTION

FIG. 1 is a front perspective view of the device;

FIG. 2 is a first side view;

FIG. 3 is a second side view;

FIG. 4 is a third side view;

FIG. 5 is a fourth side view;

FIG. 6 is a bottom view; and,

FIG. 7 is a top view.

The broken lines shown in the drawings show portions of the tile alignment and leveling device that form no part of the claimed design.
